UNITED STATES PATENT OFFICE

147,229

DESIGN FOR A CHILD'S BICYCLE AND
SIDECAR COMBINATION

Harry E. Eisele, South Pasadena, Calif.

Application May 27, 1946, Serial No. 130,106

Term of patent 14 years

(Cl. D34—15)

To all whom it may concern:

Be it known that I, Harry E. Eisele, a citizen of the United States, residing at South Pasadena, in the county of Los Angeles and State of California, have invented a new, original, and ornamental Design for a Child's Bicycle and Sidecar Combination, of which the following is a specification, reference being had to the accompanying drawing, forming a part thereof.

Figure 1 is a perspective view of a child's bicycle and sidecar combination embodying my new design.

Figure 2 is a top plan view.

Figure 3 is a side elevation.

I claim:

The ornamental design for a child's bicycle and sidecar combination, substantially as shown.

HARRY E. EISELE.
